US00D935046S

(12) United States Design Patent (10) Patent No.: US D935,046 S
(45) Date of Patent: * Nov. 2, 2021

(54) MASSAGER

- (71) Applicant: Shenzhen Violet Intelligent Communication Co., Ltd., Shenzhen (CN)
- (72) Inventor: Yin Wang, Shenzhen (CN)
- (73) Assignee: Shenzhen Violet Intelligent Communication Co., Ltd., Shenzhen (CN)

() Term: 15 Years

(21) Appl. No.: 29/714,124

(22) Filed: Nov. 21, 2019

(30) Foreign Application Priority Data

May 22, 2019 (CN) 201930253890.0

(51) LOC (13) Cl. 28-03

(52) U.S. Cl.

USPC D24/215

(58) Field of Classification Search

USPC D24/215, 200, 211, 212, 213, 214, 133, D24/188, 107, 231
